CASING FOR A WRITING INSTRUMENT

William E. Danjczek, Easton, Pa., assignor to Rapido-graph, Inc., Bloomsbury, N.J., a corporation of New Jersey

Filed July 1, 1968, Ser. No. 12,672

Term of patent 14 years

Int. Cl. D19—06

U.S. Cl. D74—17

FIG. 1

FIG. 2

FIG. 3

FIG. 1 is a perspective view of a casing for a writing instrument showing my new design;

FIG. 2 is a top plan view; and

FIG. 3 is a bottom plan view thereof.

I claim:

The ornamental design for a casing for a writing instrument, as shown.
